UNITED STATES PATENT OFFICE.

CHARLES M. BURR, OF BARDANE, WEST VIRGINIA.

COMBINATION TOBACCO AND MATCH BOX.

1,241,340.

Specification of Letters Patent. Patented Sept. 25, 1917.

Application filed May 3, 1916. Serial No. 95,149.

To all whom it may concern:

Be it known that I, CHARLES M. BURR, a citizen of the United States, residing at Bardane, in the county of Jefferson and State of West Virginia, have invented certain useful Improvements in Combination Tobacco and Match Boxes, of which the following is a specification, reference being had therein to the accompanying drawing.

10 This invention relates to improvements in combination tobacco and match boxes, one object of the invention being the provision of a tobacco box carrying in the lid thereof a novel arrangement of match box and 15 striker which will place at the command of the smoker matches and also a striker in such a location as to permit of the easy ignition of the match without the danger of the wind blowing out the same.

20 A further object of this invention is the provision of a simple and inexpensive device of this character which is thoroughly efficient and practical in use.

25 In the accompanying drawings:—

Figure 1 is a perspective view of the complete box with the lid open showing the match receptacle.

30 Fig. 2 is a longitudinal sectional view through the cover and match box.

35 Referring to the drawings, the numeral 5 designates the box proper for the tobacco, the upper edge of which is cut away as at 6 and is provided with the hinging ferrules or sleeves 7 for the reception of the hinging rod 8 which fits in the sleeves or ferrules 9 of the lid or cover 10.

40 Mounted by an adhesive or other means within the cover is the match box or receptacle 11 which is preferably made from a piece of abrasive paper, as for instance sand paper, and is folded to provide the attaching flap 12 and the front section 13, with the side wall portions 14 folded and adhesively 45 attached to the flap. The abrasive surface is so arranged as to be upon the exterior and thus be exposed, while the smooth face is upon the inside of the box for receiving the matches and reducing the danger of 50 accidental ignition thereof.

This box as shown is of lesser length than the lid so that the matches may be readily inserted therein and extracted therefrom, as the open space between the end of the box and the rim of the lid is of sufficient 55 size to permit of the introduction of the thumb and forefinger during the removal of the match. The side walls of the box are spaced from the adjacent sides of the cover to permit of the sides of the cover to telescope the walls of the body. With this construction and arrangement, a match receptacle and striking device is provided with each tobacco box so that the smoker has at hand the matches and the means for striking 60 the same, and as the lid is hinged to the box the same may be opened and the lid and box proper be used as a wind shield when lighting the pipe or cigarette.

What I claim as new is:—

In a device of the class described in combination a can, a lid adapted to close said can and having four flanges, said lid being hingedly mounted on one edge of said can, a match striker formed entirely from 75 a sheet of sand paper, said sheet of sand paper having folded sides adapted to form a box of lesser length and width with respect to the length and width of said cover, the base portions of said box having their 80 rough surface adhesively secured to the bottom of said cover so as to have an outer smooth surface forming the bottom of said box and whereupon the sides of said box are spaced from the side flanges of the cover 85 to allow the flanges of the cover to engage the sides of the can, said box receiving a series of loosely arranged matches and being of a lesser length with respect to the latter 90 so that portions of said matches may project outside of the box and be also spaced apart from the adjacent transverse flange of said cover so as to provide a space in which said matches may be manipulated for removal by a sliding movement upon the 95 bottom of the lid, the outer exposed or top side of said box having a sand paper surface.

In testimony whereof I affix my signature.
CHARLES M. BURR.
